MINE LOADING APPARATUS

Gilbert Smith, Fayetteville, W. Va.

Application January 28, 1938, Serial No. 187,531

1 Claim. (Cl. 214—63)

This invention appertains to new and useful improvements in loading apparatus especially adapted for use in mines for loading coal, ores, etc.

5 The principal object of the present invention is to provide means whereby mined material can be easily loaded onto mine cars, where the workings are in a direction laterally of the car tracks.

Another important object of the invention is 10 to provide loading means of the character stated which will be easy to operate and which will require a minimum of man power.

These and various other important objects and 15 advantages of the invention will become apparent to the reader of the following specification.

In the drawings:—

Figure 1 represents a horizontal sectional view through the workings of a mine showing in plan the tracks and a lateral working area in relation thereto.

Figure 2 is a vertical sectional view through the mine showing in side elevation the loading apparatus.

Figure 3 is a fragmentary vertical sectional view through the loading apparatus.

Figure 4 is a plan view of one of the pans.

Figure 5 is a side elevational view of one of the pans.

Figure 6 is a cross sectional view taken substantially on the line 6—6 of Figure 4.

Referring to the drawings wherein like numerals designate like parts, it can be seen that numeral 5 denotes the tunnelway through which the tracks 6 of the mine car system extend. 35 Numeral 7 denotes a side working laterally of this tunnel 5 and into which the loading mechanism protrudes as is clearly shown in Figure 1.

This loading apparatus consists of an elevated frame mounted upon the posts 8 which maintain 40 the frame 7 elevated above the tracks 6. This frame 7 is so elevated as to permit the cars 9 to avoid the same as they pass thereunder and when loaded.

Extending downwardly from one end of the 45 frame 7 is the ramp 10 along which can be pulled the pans 11.

As shown in Figure 6 each of the pans 11 consists of a shallow box-like structure having side walls 12—12 and end walls 12'—12'. The 50 swingable bottom sections 13—13 are hinged to connect to the side walls 12—12 and are free to drop when the pan passes into the frame 7. The bottom sections 13—13 are equipped with runners 13a. As is clearly shown in Figure 2,

over each of the trackways 6 the frame 11 has a pair of hingedly mounted plates 14—14 which are limited in their downward disposition by chain sections 15. This forms a chute for guiding the mined material into the cars 9 and also serves 5 to close the bottom sections as the pan is pulled from over one track to the other.

Each end of the pan 11 has a boss 16 apertured to receive the corresponding end of the cable 17. This cable extends from one pan over 10 the frame 7 and pulley 18 to the double windlass drum 19 mounted upon the floor of the mine. The cable extends backwardly under the trackways 6 and is guided by the pulley 20 to a point laterally of the pan being filled where it passes 15 around the pulley 21 to attach to the pan being filled.

It can now be seen, that when the windlass drum 19 is operated, the pan 11 which has been filled, is pulled up the ramp 10 and as it rides 20 onto the frame 7, the bottom sections 14 are released so that the contents of the pan are released into the underlying car 9.

Reverse operation of the windlass drum will 25 return the pan which can be detached and the other pan now loaded can be attached to the cable.

While the foregoing specification sets forth the invention in specific terms, it is to be understood that numerous changes in the shape, size 30 and materials may be resorted to without departing from the spirit and scope of the invention as claimed hereinafter.

Having described the invention, what is 35 claimed as new is:—

Loading apparatus for use in mines comprising 40 an open elevated frame, a ramp extending to the top of the frame, a pan having a downwardly opening hinged bottom, and means to pull the pan up said ramp onto the frame, said frame 45 having thereon in the path of movement of the pan a plurality of pairs of downwardly inclined gates forming open bottom hoppers below the pan for the discharge of contents of the pan therethrough selectively and providing for downward opening of the bottom of the pan when the latter is located over the same, said pairs of gates acting under movement of the pan in opposite directions, respectively, from such location to cam said bottom of the pan into closing 50 position, the gates being hinged to the frame for upward swinging movement into closing position.

GILBERT SMITH.
